HIGH SPEED SPINDLE

Lavern J. Jordan, Fairview Village, and Clarence C. Walters, Cleveland, Ohio, assignors to Industrial Rayon Corporation, Cleveland, Ohio, a corporation of Delaware

Original application July 10, 1935, Serial No. 30,654. Divided and this application December 29, 1937, Serial No. 182,324

12 Claims. (Cl. 308—169)

This invention relates to improvements in cap-spinning and similar twisting frames. The present application, a division of a prior application which has issued as Patent No. 2,135,519 for 5 "High speed spindle," is more particularly directed to means for lubricating the spinning frame mechanism. Among other things, the invention provides improved means for lubricating the moving parts of the spinning frame, said 10 means being mechanically simple, positive in operation, and of such a character as to require little or no adjustment. Other objects will appear as the description of the invention proceeds.

The increasingly high operating speeds of 15 textile spinning frames occasions difficulties in adequately lubricating the bearings thereof. These difficulties the present invention overcomes by providing a reservoir formed as an integral part of the bolster and one or more pockets in the spindle itself to which lubricant is fed from 20 the reservoir when the bolster mounted on the reciprocating lifting rail is in juxtaposition to said pockets. The relative reciprocating motion of the spindle and bolster effectively delivers 25 lubricant to the bearing surfaces, thereby lubricating and cooling them.

The following description is directed to but one of a number of possible embodiments of the invention.

30 Figure 1 of the accompanying drawing illustrates a sectional elevation of a cap-spinning frame corresponding to the line 1—1 of Figure 2. Figure 2 is an enlarged sectional plan taken on the line 2—2 of Figure 1. Figure 3 is a sectional elevation taken on the line 3—3 of Figure 2 of the mounting of the bolster on the lifting rail with parts omitted for the sake of clearness. Figure 4 is an enlarged sectional plan taken on the line 4—4 of Figure 1 showing means for preventing 35 relative rotation of the bolster and the spindle. Figure 5 is a sectional elevation of a brake actuating mechanism taken substantially on the line 5—5 of Figure 2.

In the drawing, in which like reference characters refer to like parts in all figures, spindle 1, 45 resiliently connected to the fixed rail 3, serves to support cap 4. Bolster 5, which is resiliently mounted on lifting rail 2, supports rotatable whirl 6, which is driven by some suitable means, as by 50 belt 7. The whirl 6 is mounted on anti-friction bearings 8 and 9. Thread bobbin 10 is supported on the bobbin-tube 11 of the whirl 6 and is held in place by means of pins 12. Relative rotation of the spindle 1 with respect to the bolster 5, 55 which is adapted to slide on the spindle 1, is pre-

vented by some such means as the pin 13, in the bolster 5, which slides in a keyway 14 in the spindle 1. As shown in Figures 1 and 4 the pin 13 is held in place by means of the spring ring 15 fitting into groove 16 of the bolster.

As shown in Figures 1 and 3, one method of mounting the bolster on the rail employs a flanged portion 17 on the bolster 5 which, projecting through opening 23, is constantly urged against the lifting rail 2 by means of a plurality of springs 18. These springs bear against the other side of the lifting rail 2 and against the heads of the bolts 19, inserted through holes 22 in fixed rail 2 and tapped into the flange 17 and locked with jam nuts 20. A resilient washer 21 made of some material such as cork may be provided, if desired, between the flange 17 and fixed rail 2. By adjustment of the bolts 19, the spring pressure and consequent freedom of bolster movement with respect to fixed rail 2 can be 20 controlled as desired.

On fixed rail 3 the spindle mounting consists of a stop 24 mounted on the spindle 1 held against the rail by spring 25, which bears against the other side of the rail and against another stop 26 mounted on the spindle. A resilient washer 27, which may be made of some such material as leather, may be provided if desired between fixed rail 3 and the stop which bears against it. Stops 24 and 26 may be nuts, provided with jam 30 nuts 28, as shown, for the purpose of adjustment of their axial position on the spindle shaft 1. The spindle 1, as shown, is non-rotatable, since it is prevented from rotating in the bolster 5, which itself is non-rotatable because it is held 35 by bolts 19.

In the base of the bolster 5 is a lubricant reservoir 29 which communicates by a passage 30 with the lubricant receiving pockets 31 and 32 in the spindle, more especially when the lifting rail 2 is 40 in its uppermost position. When lifting rail 2 is in its lowermost position, the lubricant pockets 31 and 32 will be above the top edge 33 of the bolster, allowing the lubricant to run out and down over the upper bearing 8. This lubrication 45 of the upper bearing is facilitated by the fact that the top edge 33 of the bolster, which may, if desired, be beveled, will serve to scrape off any lubricant on the spindle 1 as the lifting rail 2 moves upward.

After the lubricant has passed through the upper bearing 8, part of it is thrown off by centrifugal force to the inside wall 34 of the whirl 6 while part of it runs down the outside surface 35 of the bolster. The lubricant then progresses 50 55

downward due to the action of gravity to the lower bearing 9 which it lubricates, passes through the bearing, and back into the reservoir

29. The lower bearing 9 is also lubricated by 5 lubricant drawn up from the reservoir 29 by the action of the moving elements of the bearing 9 as it rotates. When lubricant pockets 31 and 32, filled with lubricant, slide within the bolster due to the relative reciprocation of the bolster 10 and spindle, the bearing surfaces of the bolster and spindle will also be lubricated.

Complete lubrication of all moving parts in the spinning frame is thereby secured. The 15 higher the speed at which the spinning frame operates, the better the lubrication: as the speed of rotation is increased, the action of the elements of bearing 9 in drawing lubricant from the reservoir 29 becomes more pronounced; as the 20 speed of reciprocation is increased, more lubricant is supplied over the top of the bolster to the bearings. It can be seen that no adjustments of the 25 lubricating apparatus are required, that such apparatus is simple, automatic and positive in operation, and that there is nothing to get out of order.

In the brake apparatus shown in Figures 2 and 5, which is provided to stop the spinning frame to 30 change bobbins or for other reasons, the brake arms 37 and 38 are each pivoted at one end about a pivot member, such as bolt 39. The other ends of the members are provided with holes in which the pin 40 is slidably held. This pin is slidably mounted in a boss 41 in the bolster against which 35 bear the spacing springs 42 which are supported at their outer ends in sockets 43 in members 37 and 38. One end of the pin 40 is threaded into adjusting nut 44 provided with a wedge portion 45 fitting into a corresponding depression in the member 38. This wedge portion 45 causes the member 38 to be self-adjusting with respect to the pin 40.

On the other end of the pin 40 is pivotally 40 mounted a means of actuating the brake, such as a handle 46, which has a cam-shaped portion 47 bearing against the outer surface of the member 37 in a guiding groove 48 provided there. When the handle 46 is turned to a position such as dotted position 46', the pin 40 draws the brake arm 50 38 toward the whirl, while the cam 47 forces the brake arm 37 toward the whirl, and the brake apparatus takes some position as indicated by the dot-and-dash lines of Figure 2. When the brake is thus operating, the contact surfaces 49 of the 55 brake arms, which may be of some friction-resisting material such as leather, are forced against the whirl, bringing it to a rapid halt. When the handle 46 is returned to its "off" position, as shown in full lines, the springs 42 force 60 the brake arms 37 and 38 away from the whirl and disengage the brake. Of course the handle 46 may be operated mechanically or by hand.

Reference may be had to the parent application of which this is a division for a more complete and detailed description of the mounting means described and shown herein.

The apparatus described above obviously represents but a single embodiment illustrating the preferred type of construction selected from 70 among the numerous possible embodiments of the invention. Various changes and modifications may be made without departing from the spirit of the invention or from the scope of the claims. It is intended that the patent shall cover, by suitable expression in the appended claims, whatever

features of patentable novelty reside in the invention.

What is claimed is:

1. Twisting apparatus comprising an upright spindle; a bolster disposed about and reciprocable relatively to said spindle; a lubricant reservoir in said bolster; a rotatable whirl mounted on said bolster; anti-friction bearings on said bolster supporting said whirl, the lowermost of said bearings being positioned above the level of lubricant in said lubricant reservoir; at least one lubricant-receiving pocket in said spindle for receiving lubricant from said lubricant reservoir and discharging said lubricant above said bolster; and means for conducting the discharged lubricant to said bearings and thence back to said lubricant reservoir, the mutually contacting surfaces of said bolster and spindle being lubricated from the lubricant-receiving pocket in said spindle. 20

2. Twisting apparatus comprising an upright spindle; a bolster mounted about and reciprocable relatively to said spindle; a whirl rotatably carried by said bolster; bearing means by which said whirl is carried by said bolster out of contact with said spindle; a lubricant reservoir carried by said bolster below said bearing means; means operating through the agency of said spindle during its reciprocation relative to said bolster for conducting lubricant upward within said bolster from said lubricant reservoir to said bearing means; and means directing the flow of such lubricant outside of said bolster back to said lubricant reservoir. 30

3. Twisting apparatus comprising an upright spindle; a bolster mounted about and reciprocable relatively to said spindle; a whirl rotatably carried by said bolster; bearing means by which said whirl is carried by said bolster; a lubricant reservoir carried by said bolster; and lubricating means including at least one recess in said spindle for receiving lubricant from said reservoir, conducting the lubricant to said bearing means during relative reciprocation of said spindle and said bolster, and returning such lubricant to said lubricant reservoir. 40

4. Twisting apparatus comprising an upright spindle; a bolster mounted about and reciprocable relatively to said spindle; a whirl rotatably carried by said bolster; bearing means by which said whirl is carried by said bolster; a lubricant reservoir carried by said bolster below said bearing means; and lubricating means including at least one recess in said spindle for receiving lubricant from said reservoir and conducting it during relative reciprocation between said bolster and said spindle to a point above said bolster from which it can flow by gravity through said bearing means to said lubricant reservoir. 50

5. Twisting apparatus comprising an upright spindle; a bolster mounted about and reciprocable relatively to said spindle; a whirl rotatably carried by said bolster; bearing means by which said whirl is carried by said bolster; a lubricant reservoir carried by said bolster below said bearing means, said lubricant reservoir communicating with said spindle; and at least one recess in said spindle adapted to receive lubricant from said lubricant reservoir when said spindle is in the vicinity of one of its extreme positions with respect to said bolster end, when said spindle is in the vicinity of its other extreme position with respect to said bolster, to discharge lubricant above said bearing means at a point whence such 70 75

lubricant can pass through said bearing means to return to said lubricant reservoir.

6. Twisting apparatus comprising an upright spindle; a bolster mounted about and reciprocable relatively to said spindle; a whirl rotatably carried by said bolster out of contact with said spindle; a lubricant reservoir disposed below said whirl; means operating through the agency of said spindle during its relative reciprocation with respect to said bolster for conducting lubricant from said lubricant reservoir upward through said bolster to the bearing surfaces by which said whirl is rotatably carried by said bolster; and means whereby such lubricant is permitted to flow by gravity outside said bolster back to said lubricant reservoir.

7. Twisting apparatus comprising an upright spindle; a bolster mounted about and reciprocable relatively to said spindle; a whirl rotatably carried by said bolster; bearing means by which said whirl is carried by said bolster; a lubricant reservoir disposed below said whirl; means for supplying lubricant from said lubricant reservoir to at least one recess in said spindle when said bolster is in the vicinity of its uppermost position with respect to said spindle, said recess in said spindle being adapted to discharge such lubricant to said bearing means when said bolster is in the vicinity of its lowermost position with respect to said spindle; and means whereby such lubricant is permitted to flow by gravity back to said lubricant reservoir.

8. Twisting apparatus comprising a vertical spindle; a bolster mounted about and reciprocable relatively to said spindle; a whirl rotatably carried by said bolster; bearing means by which said whirl is carried by said bolster; a lubricant reservoir disposed below said whirl; means associated with said bolster for supplying lubricant to said spindle; means causing said spindle to conduct such lubricant upward relative to said bolster to a point above said bearing means to supply such lubricant to said bearing means; and means whereby such lubricant may flow by gravity back to said lubricant reservoir.

9. Twisting apparatus comprising an upright spindle; a bolster mounted about and recipro-

able relatively to said spindle; a whirl rotatably carried by said bolster; bearing means carrying said whirl in such manner that it is spaced from and capable of rotation about said spindle; a lubricant reservoir disposed below said bearing means; means associated with said bolster for supplying lubricant to said spindle; means operating through the agency of said spindle during its relative reciprocation with respect to said bolster for conducting such lubricant to a point above and to discharge it upon said bearing means; and means for conducting such lubricant back to said lubricant reservoir.

10. Twisting apparatus comprising an upright spindle; a bolster mounted about and reciprocable relatively to said spindle; a whirl rotatably carried by said bolster; bearing means by which said whirl is carried by said bolster; a lubricant reservoir disposed below said bearing means; means associated with said bolster for supplying lubricant to the portion of said spindle passing through said bolster; means operating through the agency of said spindle during its relative reciprocation with respect to said bolster for conducting such lubricant through said bolster to a point above and to discharge it upon said bearing means; and means for conducting such lubricant back to said lubricant reservoir through a path outside said bolster.

11. Apparatus of the character described in claim 10 in which said bolster is slidably mounted on said spindle and in which said means actuated by the relative reciprocation of said bolster and spindle includes a lubricant-containing recess at the juncture of the contacting surfaces of said bolster and spindle.

12. Apparatus of the character described in claim 4 in which said bolster is slidably mounted about said spindle and in which said recess is disposed in juxtaposition to the surface of said bolster during relative reciprocation of said bolster and spindle, whereby lubricant carried by said recess serves to lubricate the sliding surfaces of said bolster and spindle.

CERTIFICATE OF CORRECTION.

Patent No. 2,229,809.

January 28, 1941.

LAVERN J. JORDAN, ET AL.

It is hereby certified that error appears in the printed specification of the above numbered patent requiring correction as follows: Page 2, second column, line 72, claim 5, for the word "end" read --and--; and that the said Letters Patent should be read with this correction therein that the same may conform to the record of the case in the Patent Office.

Signed and sealed this 25th day of February, A. D. 1941.

(Seal)

Henry Van Arsdale,
Acting Commissioner of Patents.
